ELECTRIC INCANDESCENT LAMP

Herman E. Hermanson, East Cleveland, and
 Fredrick S. Lamb, Cleveland Heights, Ohio,
 assignors to General Electric Company, a cor-
 poration of New York

Application January 2, 1951, Serial No. 203,837

6 Claims. (Cl. 313—274)

1

Our invention relates to electric incandescent lamps and similar devices, and more particularly to a mount structure therefor. The invention is of particular utility in connection with electric incandescent lamps of the double-ended tubular type having a base at each end and a filament extending longitudinally of the lamp, such as shown and described in U. S. Patent 2,032,791, Cartun, and 2,158,949, Blake, assigned to the assignee of the present invention.

Lamps of the above-mentioned double-ended tubular type are in general use at present and comprise a tubular glass envelope having metal end caps or bases sealed to the opposite ends thereof and an elongated mount supported within the envelope between the metal end caps. The mount comprises an elongated filament extending longitudinally of the envelope and supported at a plurality of spaced points along its length by a number of anchor wires insulatively fastened, by means of glass beads, to an elongated stay member which is resiliently compressible longitudinally between and supported in place by the end caps of the envelope. The stay member comprises a main or center section preferably formed of a metal channel so as to possess adequate rigidity and provided at its opposite ends with terminal wires or end conductors which are electrically connected to the ends of the filament and which bear against the end caps to make electrical connection therewith.

Heretofore, the glass support beads for the filament anchor wires of such lamp mounts have been attached or fastened in place on the metal channel by means of a fused seal therebetween, the glass beads being securely held in place by the bond between the glass and the metal of which the channel is formed. Such a fused seal type of attachment of the glass beads to the metal channel requires the use of a suitable metal for the channel which will readily "wet" and adhere to the glass of which the support beads are made. Up to the present the metal most suitable and preferably employed for this purpose has been a special high-chrome iron alloy of the so-called stainless steel type. Such a material, however, is quite expensive, thus adding materially to the cost of the finished lamp.

It is an object of our invention, therefore, to provide an electric incandescent lamp of the above-mentioned general type having a mount structure of simple and relatively inexpensive construction and easy to fabricate.

Another object of our invention is to provide an electric incandescent lamp of the above-men-

2

tioned general type having a lamp mount in which the glass beads which support the filament anchor wires are fastened to the stay member of the mount by means of a mechanical interlock therebetween.

According to the invention, the opposite side walls of the channel-shaped stay member of the lamp mount are deformed laterally of the channel at corresponding opposite points spaced therealong, as by inward or outward indentations therein, to form locking shoulders thereon which are at least partially embedded in the glass support beads for the anchor wires to thereby key and mechanically lock the glass beads in place on the channel.

Further objects and advantages of our invention will appear from the following description of a species thereof and from the accompanying drawing.

In the drawing, Fig. 1 is a longitudinal sectional view, partly in elevation, of an electric incandescent lamp according to the invention; Fig. 2 is an enlarged fragmentary perspective view of the mount structure of the lamp shown in Fig. 1; Fig. 3 is an enlarged transverse section of the mount structure taken on the line 3—3 of Fig. 2; and Fig. 4 is a sectional view illustrating the method of forming the glass beads and attaching them to the channel member of the mount structure.

Referring to the drawing, the lamp there shown is of the double-ended tubular type shown in the above-mentioned U. S. Patents 2,032,791 and 2,158,849, and comprises an elongated sealed envelope 1 consisting of a tubular glass bulb 2 having disc-shaped metal end caps or bases 3, 4 fusion-sealed to its opposite ends to form end walls for the envelope and contact terminals for the lamp. The said end caps or discs 3, 4 are preferably made of a metal alloy which has a coefficient of expansion approximately the same as that of the glass of which the tube 2 is made and which seals readily thereto by fusion. For a soft glass tube 2, the end caps 3, 4 are preferably made of a chrome-iron alloy containing about 25-30% chromium. The end caps 3, 4 are preferably concave or dish-shaped so that they may be made of thin material while retaining adequate strength, and they are provided with centrally located bosses 5, 6 which project axially inward of the envelope 1. The envelope 1 is exhausted through an aperture 7 at the center of the end cap 3, the said aperture being sealed by a mass of glass 8 which constitutes the tipped-off residue of a glass exhaust tube and

which is sheltered within the cavity formed by the boss 5.

Mounted within and extending longitudinally of the envelope 1 is an elongated lamp mount 9 according to the invention comprising a filament support structure 10 and an elongated filament 11 supported thereby. The filament support structure 10 comprises a stay member 12 composed of an elongated straight center section 13 extending longitudinally of the tube 2 adjacent the wall thereof and provided at its opposite ends with terminal wire or conductor extensions 14, 15. The center section 13 of stay member 12 is preferably in the form of an approximately V-shaped channel member to one end of which the terminal wire 14 is electrically connected as by welding. The other terminal wire 15 is insulatively secured to the other end of the channel member 13 by a short length of glass rod 16 in which the respective ends of the channel member 13 and wire 15 are embedded.

As shown, the terminal wires or end conductors 14, 15 extend from the opposite ends of the channel member 13 at a slight angle relative thereto, and their free or outer ends are bent to extend transversely of the channel member 13 and are formed into loops 17 which encircle the bosses 5, 6 on the respectively adjacent end caps to thereby position the lamp mount 9 within the envelope 1 with the filament 11 extending more or less axially of the said envelope. The loop 17 on one or both terminal wires 14, 15 is initially formed with a slight pitch or spiral shape, i. e., it is formed as a coil of less than one full turn, for the purpose of making the stay member 12 resiliently compressible to a slight extent longitudinally thereof. During the manufacture of the lamp, the spiral-shaped loop or loops 17 more or less flatten out as the stay member 12 is compressed between the opposite end caps 3, 4, the loops 17 thus resiliently bearing against the concave inner side of the end caps and so making good electrical contact therewith.

The filament 11 is in the form of a coiled tungsten wire which extends substantially the entire length and axially of the envelope 1 and is stretched out and clamped or otherwise electrically connected at its ends to short spur wires 18, 19 welded to the terminal wires 14, 15, respectively. The filament 11 is additionally supported at intermediate points along its length by one or more support or anchor wires 20 extending from the channel member 13 at spaced points therealong, the said support wires being provided at one end with filament supporting loops 21 and being secured at their other ends and insulated from the channel member by means of small glass support beads 22 in which the support wires 20 are embedded.

In accordance with the invention, the glass beads 22, in place of being fastened to and held in place on the channel member 13 by means of a fused glass-to-metal seal as has heretofore been the practice, are mechanically anchored to the channel member instead. For such purpose, the channel member 13 is formed, at spaced points along its length corresponding to the location of the glass beads thereon, with locking shoulders provided, in this instance, by small lateral deformations or indentations 23 in one or both of the side walls 24 of the channel member 13, preferably at their upper or free edges 25, as shown. The said indentations 23 are preferably provided in both of the side walls 24 of the channel at corresponding opposite points

spaced along its length. The glass beads 22 engage and are immovably held in place on the channel member 13 by the said locking shoulders, the glass beads substantially filling the interior cross-sectional space of the channel at the respective indentations 23 (Fig. 3) so as to engage and be locked in place on the channel member 13 by the indentations. As shown in Fig. 3, the glass of the beads 22 preferably extends over the free longitudinal edges 25 of the channel member 13 and down around the outer sides thereof, as indicated at 26, so as to actually embed the indented edge portions 23 of the channel member. The result, therefore, is a secure and strong clamping mechanical interlock of the glass bead to the channel such as effectively holds the bead immovably in place on the channel.

As shown in Fig. 4, the glass beads 22 are each formed from a short length of relatively small diameter glass rod or a pressed powdered glass pellet 27. The glass rod 27 is suitably heated at one end to a plastic condition and the said heated end then pressed down into the channel member 13 (which is also preferably heated to a slight degree) at the region of the respective group of indentations therein so as to cause the softened glass to substantially fill the interior cross-sectional space of the channel at said point (Fig. 3) and also flow down over the outside surfaces of the side walls 24 of the channel member, as shown at 26 in Fig. 3, thus embedding the indented edge portions 23 of the channel member in the glass and thereby securely locking the glass bead to the channel member. After the attachment of the glass rods 27 to the channel member 13, the upper ends of the rods 27 are heated to a plastic condition and fused down, whereupon the support wires 20 are inserted endwise into and embedded in the glass to complete the support wire mounting.

Inasmuch as the attachment of the glass beads 22 to the channel member 13 is customarily effected by automatic means such as causes the location of the glass beads lengthwise of the channel member 13 to vary within small limits, it is preferable that a series or group (e. g., two or three) of contiguous indentations 23 be provided in the channel member 13 at the approximate location of each bead 22 so as to allow for any such slight variation in bead location and assure that the glass bead will engage or embed at least a part of one or more of the indentations 23 of its respective group and become locked to the channel.

The mechanical fastening of the glass beads 22 to the channel member 13 in accordance with the invention therefore permits the use of an ordinary and much less expensive metal for the channel member than the high chrome-iron alloy heretofore employed for such purpose. Thus the channel member 13 may be formed of ordinary rolled iron or steel, for instance, as a result of which the cost of the lamp mount 9 and of the finished lamp is considerably reduced.

Although a preferred embodiment of our invention has been disclosed, it will be apparent that the invention is not to be limited to the specific construction and arrangement of parts shown but that they may be widely modified within the spirit and scope of our invention as defined by the appended claims.

What we claim as new and desire to secure by Letters Patent of the United States is:

1. An electric lamp comprising a glass envelope, a mount within said envelope comprising an

elongated filament and an elongated metallic stay member extending longitudinally of the filament and carrying support wires engaging and supporting the filament at spaced points therealong, said stay member comprising a metal channel provided at spaced points therealong with lateral deformations in at least one of its side walls, and glass beads insulatively fastening said support wires to said channel, said channel being of a metal incapable of readily forming an adherent bond with the glass of said beads, and said glass beads being shaped in situ in engaging and interlocking relation with the said deformations to mechanically hold the beads immovably in place on said channel against movement longitudinally as well as laterally thereof.

2. An electric lamp comprising a glass envelope, a mount within said envelope comprising an elongated filament and an elongated metallic stay member extending longitudinally of the filament and carrying support wires engaging and supporting the filament at spaced points therealong, said stay member comprising a metal channel provided with longitudinally spaced indentations in at least one of its side walls, and glass beads insulatively fastening said support wires to said channel, said channel being of a metal incapable of readily forming an adherent bond with the glass of said beads, and said glass beads substantially filling the interior cross-sectional space of said channel at the region of respective ones of said indentations and being shaped in situ in engaging and interlocking relation with the said indentations to mechanically hold the beads immovably in place on said channel against movement longitudinally as well as laterally thereof.

3. An electric lamp comprising a glass envelope, a mount within said envelope comprising an elongated filament and an elongated metallic stay member extending longitudinally of the filament and carrying support wires engaging and supporting the filament at spaced points therealong, said stay member comprising a metal channel having the free edge portion of at least one of its side walls inwardly indented at spaced points therealong to provide locking indentations, and glass beads insulatively fastening said support wires to said channel, said channel being of a metal incapable of readily forming an adherent bond with the glass of said beads, and said glass beads substantially filling the interior cross-sectional space of said channel at the region of respective ones of said indentations and being shaped in situ into at least partially embedding relation with the indented free edge portions of said channel to mechanically lock the beads to the channel and hold them immovably in place thereon against movement longitudinally as well as laterally thereof.

4. An electric lamp comprising a glass envelope, a mount within said envelope comprising an elongated filament and an elongated metallic stay member extending longitudinally of the filament and carrying support wires engaging and supporting the filament at spaced points therealong, said stay member comprising a metal channel having the free edge portions of both its side walls indented to provide opposed sets of indentations spaced apart longitudinally of the channel, and glass beads insulatively fastening said support

wires to said channel, said channel being of a metal incapable of readily forming an adherent bond with the glass of said beads, and said glass beads substantially filling the interior cross-sectional space of said channel at the region of respective sets of said indentations and being shaped in situ into at least partially embedding relation with the latter to mechanically lock the beads to the channel and hold them immovably in place thereon against movement longitudinally as well as laterally thereof.

5. An electric lamp comprising a glass envelope, a mount within said envelope comprising an elongated filament and an elongated metallic stay member extending longitudinally of the filament and carrying support wires engaging and supporting the filament at spaced points therealong, said stay member comprising a metal channel having the free edge portions of both its side walls indented to provide longitudinally spaced groups of contiguous opposed sets of indentations, and glass beads insulatively fastening said support wires to said channel, said channel being of a metal incapable of readily forming an adherent bond with the glass of said beads, and said glass beads substantially filling the interior cross-sectional space of said channel at the region of respective groups of said indentations and being shaped in situ into at least partially embedding relation with the indentations of at least one of the said opposed sets thereof in its respective group to mechanically lock the beads to the channel and hold them immovably in place thereon against movement longitudinally as well as laterally thereof.

6. A lamp mount comprising an elongated stay member, an elongated filament extending longitudinally of said stay member and supported therefrom, a plurality of support wires carried by said stay member and engaging and supporting the filament at spaced points therealong, said stay member comprising a metal channel having the free edge portion of at least one of its side walls inwardly indented at spaced points therealong to provide locking indentations, and glass beads insulatively fastening said support wires to said channel, said channel being of a metal incapable of readily forming an adherent bond with the glass of said beads, and said glass beads substantially filling the interior cross-sectional space of said channel at the region of respective ones of said indentations and being shaped in situ into at least partially embedding relation with the indented free edge portions of said channel to mechanically lock the beads to the channel and hold them immovably in place thereon against movement longitudinally as well as laterally thereof.
